UNITED STATES PATENT OFFICE.

WILLIAM PINCKNEY FRANCIS, OF ATLANTA, GEORGIA.

REINFORCED MASONRY BEAM.

1,158,197.

Specification of Letters Patent. Patented Oct. 26, 1915.

Application filed December 23, 1914. Serial No. 878,729.

To all whom it may concern:

Be it known that I, WILLIAM PINCKNEY FRANCIS, a citizen of the United States, and a resident of Atlanta, in the county of Fulton and State of Georgia, have invented a new and Improved Reinforced Masonry Beam, of which the following is a full, clear, and exact description.

This invention relates to masonry, and 10 more particularly to a composite beam having a metallic reinforce for strengthening the brick masonry of the beam.

The invention has for its general objects to provide a beam composed of brick or 15 other blocks laid in courses and united by mortar or other bonding material, and in the beam is a reinforcing structure of novel form, whereby great strength is obtained with a minimum of material, and whereby 20 the bricks can be laid in an easy and expeditious manner.

A further object of the invention is the provision of a metallic reinforcing structure for beams, which structure is composed 25 of a plurality of bars suitably united together and having lugs struck out therefrom to enter the joints between adjacent bricks, whereby there is an effective anchorage between the masonry and reinforcing element.

Another object of the invention is the 30 employment in connection with the reinforcing bars of upwardly-extending looped members which are embedded in the masonry to reinforce and stiffen the same 35 against vertical and horizontal stresses, such looped members being so disposed as to lie in the plane of the joints between the rows or courses of bricks so that it will be unnecessary to cut or break the bricks in building up the masonry.

With such objects in view, and others which will appear as the description proceeds, the invention comprises various novel features of construction and arrangement of 45 parts which will be set forth with particularity in the following description and claims appended hereto.

In the accompanying drawings, which 50 illustrate certain embodiments of the invention and wherein similar characters of reference indicate corresponding parts in all the views, Figure 1 is a perspective view of the reinforcing structure of a beam with part of the masonry built up thereon; Fig. 2 55 is a transverse section of the beam on the

line 2—2, Fig. 1; Fig. 3 is a side view of the metallic reinforcing structure; Fig. 4 is a plan view of a portion of the beam before the top course of bricks is laid; Fig. 5 is a transverse section of a modified form of 60 beam; Fig. 6 is a perspective view of a portion of the reinforcing element of the beam shown in Fig. 5; Figs. 7 and 8 are fragmentary perspective views of different forms of angle-iron stock used in the making of 65 the reinforcing structures. Fig. 9 is a fragmentary perspective view of a modified form of reinforcing element; and Fig. 10 is a detail perspective view of a further 70 modification.

Referring to the drawings, A designates the reinforced structure and B the masonry built up thereon. This reinforcing structure A comprises two oppositely-disposed angle-bars 1 and 2 which are arranged with the webs or flanges 3 vertical and the webs or flanges 4 horizontal. These angle-bars are parallel and spaced apart and the vertical web of each has struck out therefrom right-angularly disposed lugs or anchor elements 5 which are spaced apart a distance about the length of a brick, so that a brick will set in between every pair of lugs 5. The angle-bars 1 and 2 are united by obliquely disposed inverted U-shaped or looped connecting and stiffening elements 6 which are bent from rod stock and have their vertical members 7 formed into horizontal feet 8 which point in the same direction, as clearly shown in Fig. 3, and are anchored under the lugs 5. 80 The vertical members 7 lie flat against the vertical webs 3 of the angle bars and the horizontal connecting portion 9 between the members 7 will occupy a position between certain 85 layers of brick. The looped element 6 may be further secured to the angle bars by clip bolts 10, as shown in Figs. 1 and 2, such bolts passing through openings 11 in the vertical webs 3 of the angle bars. Clips 26 90 may take the place of lugs 5, as shown in Fig. 9.

The complete reinforcing structure is shown in Fig. 3, and it will be noted that the angle bars are united together by two groups 105 of looped elements 6, the elements of one group being oppositely disposed to those of the other group, and in the present instance each group has three looped elements, but obviously the number may be changed, as 110 circumstances require.

In constructing a beam the reinforcing structure A is mounted on suitable piers, columns or other supporting means on which the ends of the reinforcing structure rest, 5 the flanges 3 extending upwardly, as do also the looped members 6. Applied to the under side of the angle-irons are tiles 12 which are held in place by U-shaped clips 13 which extend inwardly from the side edges of the tile 10 with the upper members 14 engaging over the horizontal flanges 4 of the angle-irons, and the members 15 of the clips engaging under the tiles. Mortar is then placed on the tiles in the space between the angle-irons, 15 and a line of bricks or other blocks 16 is held in this mortar, the angle-irons being spaced apart just far enough to accommodate a brick between them. Mortar is then applied to the horizontal flanges 4 of the angle-irons, 20 and the bricks 17 are set in this mortar, each brick 17 being placed in between each pair of adjacent lugs 5 of the angle-irons. After this lower course of bricks 16 and 17 has been laid another course of 25 bricks 16 will be laid on the first course, and in this manner course after course will be laid until the beam is of the desired height. In the construction shown, the resulting beam is the width of three bricks in a course 30 and the height of four courses. The horizontal members 9 of the looped element 6 will lie between the top course of bricks and the one next below it, and the vertical members 7 will lie in the vertical bonds between 35 the superimposed lines of bricks 16 and 17.

A reinforcing structure suitable for a beam made of two vertical courses of bricks is shown in Fig. 6, and is composed of two angle-bars 18 and 19 which are oppositely disposed and set back to back, and these bars have laterally-extending lugs 20 similar to the lugs 5 of the angle-bars of Fig. 1. These lugs may be punched out from the vertical webs of the angle-bars, according to either 40 method shown in Figs. 7 and 8, or clips may be bolted on to answer the same purpose. Clamped between the angle-bars 18 and 19 is a vertical frame formed of a straight rod 20 and a waved or zigzag rod 21 that embodies vertical members 22 connected by horizontal members 23, alternate members 23 being at the top and bottom of the frame. The straight rod 20 is secured to the top 45 connecting portions 23 of the bar 21 by clips 24 or other suitable fastenings. This frame made of the rods 20 and 21 lies between the vertical courses of bricks 25 and 25' which are laid respectively on the angle-bars 18 and 19.

In Fig. 9 the laterally projecting members that extend into the joints between the bricks are formed as clips 26 which are fastened to the vertical web 27 of the reinforcing bar. In this figure the reinforcing bar is of T-shape cross-section, so that the

horizontal flanges 28 will support the courses of bricks, and in this case the loop-forming element 21 is engaged under certain of the members 26 alternately at opposite sides of the web 27.

As a further modification pins 29 may be rigidly secured to the vertical web 30 of the annular reinforcing bar, as shown in Fig. 10, such pins being adapted to extend into the joints between adjacent bricks just as 75 the lugs 5 of Fig. 1.

From the foregoing description taken in connection with the accompanying drawings, the advantages of the construction and method of operation will be readily understood by those skilled in the art to which the invention appertains, and while I have described the principle of operation, together with the structure which I now consider to be the best embodiment thereof, 85 I desire to have it understood that the structure shown is merely illustrative and that such changes may be made when desired as are within the scope of the appended claims.

Having thus described my invention, I 90 claim as new and desire to secure by Letters Patent:

1. A reinforcing structure for masonry beams, comprising a pair of parallel spaced bars each having a horizontal and a vertical flange, the vertical flanges having lugs extending outwardly therefrom and overlying the horizontal flanges, and inverted looped elements extending obliquely across the space between the bars and secured to the 100 latter.

2. A reinforcing structure for masonry beams comprising a pair of spaced parallel bars having vertical and horizontal flanges, spaced vertically disposed U-shaped elements arranged obliquely to the bars, and means for connecting the elements to the vertical flanges of the bars.

3. The combination of a pair of spaced angle-bars having vertical and horizontal flanges, tiles fastened to the bottom of the bars and closing the space between the latter, lines of mortar-embedded bricks lying on the horizontal flanges of the bars and on the tile between the bars, laterally-extending lugs on the vertical flanges extending into the joints between the bricks, and obliquely disposed U-shaped elements fastened to the bars and composed of vertical members and a horizontal member embedded in 115 the layers of brick supported on the bars and tiles.

4. A metallic reinforce for masonry beams, comprising a bar of angular form and having a horizontal brick-supporting web and a vertical web adapted to lie between rows of brick, members extending laterally from the vertical web and over the horizontal web, said members being spaced apart at such a distance as to be adapted to 125 130

enter the joints between the bricks on the horizontal web, and vertical loops extending upwardly from the vertical web of the bar.

5. A metallic reinforce for masonry beams, comprising a bar of angular form and having a horizontal brick-supporting web and a vertical web adapted to lie between rows of brick, members extending laterally from the vertical web and over the horizontal web, said members being spaced apart at such a distance as to be adapted to enter the joints between the bricks on the

horizontal web, and vertical loops extending upwardly from the vertical web of the bar, each loop being of such length longitudinally of the bar as to extend over a plurality of said laterally extending members. 15

In testimony whereof I have signed my name to this specification in the presence of two subscribing witnesses.

WILLIAM PINCKNEY FRANCIS.
